CLAIM

The ornamental design for an electric wing actuator as shown and described.

DESCRIPTION

FIG. 1 is a front, right and top perspective view of an electric wing actuator, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and top perspective view of a second embodiment of an electric wing actuator.

FIG. 10 is a rear, left and bottom perspective view of the second embodiment of the electric wing actuator of FIG. 9.

FIG. 11 is a front elevation view of the second embodiment of the electric wing actuator of FIG. 9.

FIG. 12 is a rear elevation view of the second embodiment of the electric wing actuator of FIG. 9.

FIG. 13 is a left side elevation view of the second embodiment of the electric wing actuator of FIG. 9.

FIG. 14 is a right side elevation view of the second embodiment of the electric wing actuator of FIG. 9.

FIG. 15 is a top plan view of the second embodiment of the electric wing actuator of FIG. 9; and,

FIG. 16 is a bottom plan view of the second embodiment of the electric wing actuator of FIG. 9.

The broken lines depict portions of the electric wing actuator that form no part of the claimed design.
